UNITED STATES PATENT OFFICE.

WILLIAM G. LINDSAY, OF NEWARK, NEW JERSEY, ASSIGNOR TO THE CELLULOID COMPANY, A CORPORATION OF NEW JERSEY.

DECORATED BODY AND PROCESS FOR MAKING SAME.

Application filed November 28, 1922. Serial No. 603,887.

To all whom it may concern:

Be it known that I, WILLIAM G. LINDSAY, a citizen of the United States, residing at Newark, in the county of Essex and State 5 of New Jersey, have invented certain new and useful Improvements in Decorated Bodies and Processes for Making Same, of which the following is a specification.

This invention relates to decorated articles 10 or bodies and more particularly to those formed of laminated plastic material.

Among the objects of my invention is to produce an article of this character which shall be durable in use, inexpensive to manufacture, of a particularly attractive appearance and one which shall retain its appearance indefinitely.

In the preferred embodiment of my invention I form the article from a suitable base 20 composed of a material which may be either opaque or transparent. This base serves to hold an added material which is designed to give to the finished body a distinctive appearance. An example of such an added 25 material is lustrous metal powder. In case the base is opaque the metal is carried at the surface of the base. Covering this base and the added material is a transparent or translucent lamination which is designed to 30 alter to a greater or less extent the natural appearance of the added material or of the added material and the base. Such a change in the appearance may be effected by the 35 employment of a tinted transparent lamination which will have the effect of changing the normal color of the background.

An excellent effect is produced by the employment of an opaque ivory base to the 40 surface of which has been applied, in the manner hereafter described, silver metallic scale. On this scale rests a transparent sheet which has an amber tint. The effect produced by the film of silver as seen through the outer sheet is that of gold bronze tinsel. 45 In case I employ a sheet which has a trace of blue coloring instead of the amber, the effect is that of silver tinsel.

I preferably employ for the base and 50 covering sheet a plastic soluble cellulosic material such as cellulose nitrate or acetate. I may in certain cases however employ such substances as the plastic phenol derivatives of which bakelite is an example.

As illustrative of certain embodiments of my invention reference is had to the accompanying drawing wherein—

Fig. 1 is a perspective view of a toilet article embodying the invention.

Fig. 2 is a sectional view of the same taken on the line 2—2 of Fig. 1.

Fig. 3 is a sectional view of a sheet embodying my invention.

Fig. 4 is a perspective view of a cube embodying my invention and

Fig. 5 is a section of the cube shown in Fig. 4.

In carrying out my invention the base of the object is worked up in the usual manner from suitable material such as cellulose nitrate to which has been added the pigments necessary to produce the desired color. In the case of the toilet article shown in Fig. 1 the base 10 is kneaded and rolled into a thick sheet. An ivory base also produces a very attractive appearance. This base is 75 formed of superposed adhering laminations, alternate laminations containing a certain amount of white pigment while the remaining laminations contain a somewhat less amount. In the case of the sheet material shown in Fig. 3 the base 11 may be shaved from a block or flowed and evaporated according to well-known practice. In the case of the dice shown in Fig. 5 the base 12 may be cut from a block or molded as desired. 80 In the forms shown in Figs. 1, 2, 4 and 5 the base constitutes the body portion or a part of the body portion of the article.

To the whole or part of the surface of the base there is then lightly applied a suitable 90 solvent such as amyl acetate. When the surface has become slightly moistened there is dusted over it silver metallic scale 14 which adheres to the surface or to that part of the surface to which the softening material has 95 been applied. It is not necessary in all cases that the scale be applied so thickly as to form a continuous metallic layer, as excellent effects may be produced when a portion of the background is visible through the scale. 100 The excess solvent which is here being used as a cement is then allowed to evaporate, and there is finally applied to the surface a transparent sheet 15 of cellulosic material of say 50/1000 inch thickness. In case it is 105 desired to produce the effect of silver tinsel

this sheet has a trace of blue coloring. If however the effect of gold bronze is desired the sheet is colored with a small amount of amber tint, as previously stated. The amber tint referred to is that of the usual transparent amber, namely, a reddish yellow. One side of this sheet is treated with the solvent cement and after it has become slightly softened the side carrying the cement 10 is pressed against the surface of the base. The sheets thus assembled are placed in a press and allowed to remain until the union is thoroughly effected. The resulting sheet is then removed from the press and cut up 15 into blocks for toilet articles such as brush backs, mirrors, combs, boxes and the like and further worked up according to means known to those skilled in the art.

I apply the metal to the surface rather 20 than working the same into the base as a greater amount of lustre is produced with a given amount of metal.

This application is a continuation in part 25 of my co-pending application Serial No. 589,143, filed September 19, 1922.

I claim:

1. Decorated material comprising an opaque base, a layer of divided lustrous scale material adherent to said base, a transparent plastic sheet covering said material and firmly united to said base through spaces between the particles of lustrous material, said particles having visible faces which extend approximately in the same general direction along a smooth surface and said particles being so spaced that said material when viewed through said sheet has the appearance of a continuous lustrous surface. 30

2. Decorated material comprising a base, 40 a layer of lustrous metallic scale adherent to said base, the particles of scale lying in substantially the same plane, a transparent sheet covering said scale and firmly united to said base through spaces between the particles of scale, said scale when viewed through said sheet giving the appearance of a continuous hammered metal surface.

3. A decorated body comprising a metallic layer, a transparent plastic sheet over said layer, said sheet being tinted so as to alter 50 the appearance of said layer as viewed

through said sheet so that the same has the appearance of a precious metal.

4. A decorated body comprising a silver layer, a transparent plastic sheet over said layer, said sheet being tinted so as to alter the appearance of said layer as viewed through said sheet so that the same has the appearance of a precious metal. 55

5. A decorated article comprising an opaque cellulosic base, a layer of silver scale adherent to said base and extending to the surface of said article, a cellulose plastic transparent blue tinted sheet covering said scale, said sheet being firmly united to said base through said scale. 60

6. A laminated body comprising a base, silver scale applied to the surface thereof and a transparent sheet covering said scale, said sheet having a slight blue tint. 70

7. Method of forming a laminated structure having an intervening metal film which consists in moistening a sheet of cellulosic material with a suitable solvent, applying metal thereto to form a film, moistening a second sheet of cellulosic material with a solvent and pressing said second sheet upon said metal film. 75

8. The process of forming a solid decorative material having the toughness, strength, durability and workability of the usual pyroxylin plastics which comprises treating a sheet of plastic material with suitable cementing material, applying metal scale to the moistened surface in such quantity as will adhere thereto and covering said scale by a transparent sheet of material and firmly uniting said sheets together through spaces between the particles of scale. 85

9. The process of forming a solid decorative material having the toughness, strength, durability and workability of the usual pyroxylin plastics which comprises treating a sheet of plastic material with suitable cementing material, applying metal scale to the moistened surface in such quantity as will adhere thereto and covering said scale by a transparent sheet of material and firmly uniting said sheets together through spaces between the particles of scale by pressure. 90 95 100

WILLIAM G. LINDSAY.
